UNITED STATES PATENT OFFICE.

J. Q. C. SEARLE, OF TOPEKA, KANSAS, ASSIGNOR TO JULIA E. SEARLE, OF SAME PLACE.

IMPROVEMENT IN BASE-BURNING STOVES.

Specification forming part of Letters Patent No. 89,248, dated April 20, 1869.

To all whom it may concern:

Be it known that I, J. Q. C. SEARLE, of Topeka, Kansas, have invented certain improvements in Heaters; and I do hereby declare the following to be a full, clear, and exact description of the same.

My invention consists of a fire-pot and certain cylinders, partitions, and casings, constructed and arranged as fully described hereafter, so as to effect a thorough combustion of the fuel contained in the fire-pot, and of the gases arising from the same, and thus effectually heat the said partitions and casings and the air in contact therewith.

In order to enable others skilled in the art to make and use my invention I will now proceed to describe its construction and operation, reference being had to the accompanying drawings, which form a part of this specification, and in which—

Figure 1, Sheet No. 1, is a vertical elevation of my improved heater; Fig. 2, a transverse section on the line 1 2, Fig. 1; Fig. 3, a transverse section on the line 3 4, Fig. 1; and Fig. 4, Sheet No. 2, a sectional elevation of a modification.

The outer casing of the heater consists of the base A, the body B, and cylinder C, the latter being perforated above the line $x x$. Within the body B, and just below its junction with the cylinder C, is suspended a fire-pot, D, consisting of an inner plate, a, and an outer plate, a', and with the space y between the two plates communicate hollow arms b, extending radially to the cylinder C. Openings c in the cylinder permit the air to pass freely into the arms, which conduct it to the hollow fire-pot, and from the latter it passes to a conical tube, E, extending downward from the fire-pot through two horizontal partitions, d d', into a casing, E¹, (in the base,) which contains the ash pan or drawer E². Within the body B are arranged two annular deflectors, G G', forming an intermediate flue, t', which surround the tube E, the deflector G extending from the fire-pot nearly to the partition d, and the inner deflector G' from the partition d nearly to the fire-pot, and in the partition d, between the deflector G and the tube E, are two openings, y' y', Fig. 2.

A funnel-shaped tube or "feeder," H, ex-

tends from the top C' of the stove to a point a short distance above the arms b, and to the upper end of this feeder H is fitted a cap, H'. The lower end of the tube H is inclosed by a short shield, I, forming an air-chamber, w, which communicates with a chamber, w', between two inclined partitions, f f', extending from the shield to the cylinder C, and in the latter are perforations c¹ for the admission of air to the chamber w'. The tube H from the shield I to its upper end is surrounded by another tube, J, forming an intermediate annular chamber, v, to the upper end of which air is admitted through perforations c². The fire-pot is provided with a grate, K, which is operated by an arm, m, extending through the casings to the outside of the heater.

The space between the partitions d d' communicates with the chimney through a pipe, X. In the body B are openings u, in which are inserted sheets of mica; and the base is provided with a sliding door, n, so arranged as to allow the drawer E² to be withdrawn and replaced. The front side of the drawer E² is provided with a register, o, and in the base are openings s t, the latter near the top and the former near the bottom of the base.

When the base of the stove is closed air is supplied to the fuel through the openings c, hollow arms b, hollow fire-pot and tube E, by opening the register o; however, the air may be admitted directly to the tube E.

The heated gases and products of combustion pass from the fire-pot over its upper edge and downward between the arms b, and in contact with the outer casing of the stove, (which is thus thoroughly heated,) then upward through the flue t', between the deflectors G G'; then downward between the deflector G' and the tube E, and through the openings y' y', and between the partitions d d', to the pipe X and to the chimney.

Inasmuch as the arms b which support the fire-pot are made the means of conducting the air into the stove, they are maintained at such a temperature as not to be burned or warped by the heat of the fire, while the fire-pot is also preserved by the constant current of cold air passing into and through the same.

The air is brought into contact with the heated base and partition d' as it passes, first

through the openings *s*, then out through the openings *t*, while at the top of the heater the perforated cylinder *C* permits the air to have free access to the upper plates.

The flue *t'*, situated below the fire-pot and between the latter and the outer pipe *X*, insures an equal distribution of the draft, so that the heated gases flow uniformly over the edge of the fire-pot, and in contact with all parts of the outer casing, instead of being drawn to one side merely, as would be the case without an annular flue or opening.

The tube *H* contains a supply of coal, which is fed continuously to the fire, but is prevented from becoming heated by the constant currents of cold air which pass continuously downward through the chamber *v*, the partitions *f f'* preventing the heat from passing upward to the cylinder, while the air passing between these partitions and between the shield *I* and tube *H* prevents these parts from being burned away, and also affords a plentiful supply of oxygen to the gases as they rise from the ignited fuel.

While the shield *I*, with the tube *H*, forms an air-chamber to protect the lower end of the tube from the effects of the heat, it will be seen that it is not connected to the tube, so that the latter can be readily withdrawn to afford free access to the interior of the heater while the obstruction of the air-passages by dust, which occurs where the ordinary hollow rings are used, is prevented.

Inasmuch as the air in its passage to the fire is confined to the tube *E*, it will not cool the plates of the stove and reduce its heating capacity, as is the case where the air has free access to the interior of the ash-pits in stoves and heaters of the ordinary construction.

In some instances (as when the stove is in a railway-car) the drawer *E'* may be dispensed with, the tube *E* being extended so as to pass through the bottom of the car or to a cellar, (when the heater is arranged in a building,) the tube being provided with a sliding valve to regulate the admission of air and the withdrawal of the ashes.

Such an arrangement is shown in the modification illustrated in Sheet No. 2, in which the construction of the stove is somewhat altered, the deflector *G'* being dispensed with, the deflector *G* being closed at the bottom, forming a casing, while the fire-pot rests upon the upper edge of the tube *E*, so that air from the latter passes between the plates of the fire-pot through openings *e* to the fire, and through an annular orifice at the edge of the fire-pot to the heated gases.

It will be seen that the mica-covered openings *u* are situated below the fire-grate, at a point opposite to the flue, for the passage of the ignited gases. By this arrangement much

of the heat is radiated directly from the incandescent gases into the room, instead of being first transmitted to the stove-plates. Should it be desirable the chambers *v* and *w*, instead of serving as air-passages, may be filled with asbestos, plaster, or other non-conducting material, not in the form of slabs or cylinders, (as I am aware that cylinders of fire-brick have heretofore been used in this manner,) but in a granulated or powdered state—an arrangement peculiarly adapted for stoves which are used in places where fire-brick, when destroyed, cannot readily be replaced.

It will be apparent that my improvements may be applied to heaters of various forms, or to cooking stoves or ranges.

Without limiting myself to the precise construction and arrangement of parts herein described,

I claim as my invention, and desire to secure by Letters Patent—

1. A fire-pot suspended within a heater, substantially as described, in combination with an annular flue, *t'*, arranged as set forth.

2. A hollow fire-pot having openings at the upper edge, in combination with an air-conducting tube, *E*, for the purpose described.

3. The combination of the fire-pot and a series of hollow air-conducting tubes or arms, which support the pot, substantially as set forth.

4. The tube *E*, extending from the fire-grate through the partition *d'*, and serving both to conduct the ashes to the drawer and to prevent the access of cold air to the exterior plates of the stove.

5. The combination of the fire-pot *D*, deflectors *G G'*, and outer casing *C* of the heater, the whole being arranged substantially as and for the purpose described.

6. The combination of the above, the partitions *d d'*, openings *y y'*, and pipe *X*, all arranged as set forth.

7. The feeder *H*, in combination with the outer perforated casing *C*, substantially as and for the purpose described.

8. The feeder *H*, consisting of two eccentric tubes and an intervening chamber containing asbestos, or its equivalent.

9. The arrangement of the casing *C*, feeder *H*, and inclined partitions *f f'*, extending between the casing and feeder, and inclosing an air-space, *w'*, all as set forth.

In testimony whereof I have signed my name to this specification in the presence of two subscribing witnesses.

J. Q. C. SEARLE.
